CONTROL APPARATUS

Erik G. Erson, Wilkinsburg, Pa., assignor to The Westinghouse Air Brake Company, Wilmerding, Pa., a corporation of Pennsylvania

Application March 30, 1944, Serial No. 528,699

6 Claims. (Cl. 121—38)

1

This invention relates to control apparatus and more particularly to fluid pressure means for controlling the speed or power output and for also controlling the stopping of an internal combustion engine.

In internal combustion engines, such as of the Diesel type, which employ compressed air for controlling the starting of the engine and for controlling the supply of fuel to the engine, it is desirable when the engine is running, that a loss of the compressed air supply, due to rupture of a supply pipe or the like, will not cause the engine to stop, since it might be impossible to restart the engine. Further, such undesired stopping of the engine might result in a disaster which could be avoided, if the engine continued to run, by controlling the engine speed or output by auxiliary or emergency means such as a hand operated throttle lever on the engine.

The principal object of the invention is therefore the provision of a fluid pressure control apparatus for governing the speed and stopping of an internal combustion engine such as above described and which is so arranged as to prevent stopping of the engine in case of loss of the supply of fluid under pressure.

Other objects and advantages will be apparent from the following more detailed description of the invention.

In the accompanying drawing; Fig. 1 is a diagrammatic view, mainly in section, of a fluid pressure control apparatus embodying the invention; and Figs. 2 and 3 are sectional views of a device shown in Fig. 1 but with the parts in different positions.

Description

In the drawing the reference numeral 1 indicates a fuel control shaft of an internal combustion engine, while the numeral 2 indicates a lever for turning said shaft to different fuel control positions, such as "Stop," "Idle," and "Full speed" position, indicated on the drawing, for effecting, respectively, cutting off of fuel to the engine to stop the engine, a supply of fuel to the engine in an amount required to cause operation of the engine at a minimum or idling speed, and a supply of fuel to the engine in the amount required to cause operation of the engine at a maximum speed or maximum output of power. Adjustment of lever 2 to positions between "Idle" and "Full speed" will vary the supply of fuel to the engine to provide various speeds or degrees of power output, between the minimum and maximum.

For controlling the adjustment or positioning of the fuel control lever 2 there are provided a pneumatic speed control and stop device 3, an auxiliary or emergency speed and stop control lever 4 and a manually operative control valve device 5 for controlling the device 3.

2

The pneumatic speed control and stop device 3 comprises a casing containing a speed and stop control movable element, preferably in the form of a flexible diaphragm 6 having at one side a pressure chamber 7 open to a control pipe 8 and having at the opposite side a non-pressure chamber 9. A stem 10 articulated at 10a in chamber 9 and extending through the diaphragm 6 is provided in pressure chamber 7 with a flange 11 which engages the diaphragm. A combined follower and stop 12 is mounted over stem 10 in non-pressure chamber 9 against the diaphragm 6, and a nut 13 screw-threaded on to stem 10 is forced against the follower 12 to clamp the diaphragm between said follower and flange 11.

The diaphragm stem 10 extends through the non-pressure chamber 9 and loosely through an opening in the outer end wall thereof and outside of the casing is connected by a pin 14 to one end of a lever 15, the opposite end of which lever is connected by a pin 16 to one end of a link 17. The lever 15 is fulcrumed intermediate its ends on a pin 18 carried in one end of a link 19 the opposite end of which is mounted to turn on a pin 20 carried in a projection of the casing of the speed and stop control device 3. The opposite end of link 17 is connected by a pin 21 to the auxiliary control lever 4, while intermediate the ends of the said link there is a pin 22 connecting the link to the end of the fuel control lever 2.

As shown in the drawing, when the flange 11 on the diaphragm stem 10 is in substantial contact with end wall 23 of the pressure chamber 7, the fuel control lever 2 will be pulled to its "Stop" position through the connecting stem 10, lever 15 and link 17. As the diaphragm 6 is deflected away from wall 23 to a position defined by contact between the diaphragm follower 12 and stops 24 provided on the end wall of the non-pressure chamber 9, the lever 15 and the link 17 will pull the fuel control lever to "Full speed" position. With the diaphragm 6 in a position (Fig. 2 or Fig. 3) intermediate its positions above described, the fuel control lever 2 will assume its "Idle" position. This intermediate position will be defined in detail hereinafter.

In the combined speed and stop control device 3, the diaphragm stem 10 projects through a bore in the wall 23 into a pressure chamber 25 formed at one side of a movable element preferably in the form of a flexible diaphragm 26. The pressure chamber 25 is open to a fluid pressure supply pipe 29, so that in use said chamber will be constantly supplied with fluid under pressure. At the opposite side of diaphragm 26 is a non-pressure chamber 30. In wall 23 is disposed a sealing ring 27 having sealing sliding contact with the peripheral surface of stem 10 to prevent leakage of fluid under pressure from either of the pressure chambers 7 or 25 to the other.

In pressure chamber 25 is a cylindrical element 31 having a closed end or head 32 which engages the adjacent face of diaphragm 26. A stud 33 projects from the head 32 through a central aperture provided in diaphragm 26, and is mounted over this stud in the non-pressure chamber 30 is a combined follower and stop 34. A nut 35 provided on the stud 33 is tightened against the follower 34 and clamps the central portion of diaphragm 26 between said follower and the head 32. The follower 34 is arranged to engage the outer end wall of non-pressure chamber 30 to limit the deflection of diaphragm 26 in a direction away from diaphragm 6.

A ring 36 disposed in pressure chamber 25 is secured by screw-threaded engagement over the open end of the cylindrical element 31. The outer surface of ring 36 is slidably mounted in suitable guides 37 in the casing, and said ring is provided with a flange 38 projecting inwardly past the end of the element 31 and constituting a seat for one end of a coil spring 39 contained within the element 31. The diaphragm stem 10 projects through the central opening in ring 36 and through the spring 39 and on its end adjacent the head 32 of member 31 is secured a follower 40 against which the opposite end of spring 39 bears. This spring is initially partially compressed so as to be effective to urge the end of stem 10 against the head 32.

When chamber 25 is charged with fluid under pressure from the supply pipe 29, the diaphragm 26 will be deflected to the position in which it is shown in the drawing, which position is defined by the follower 34 engaging the casing. With the diaphragm 26 in this position and with stem 10 engaging the head 32 of member 31, as will occur with diaphragm chamber 7 open to the atmosphere in a manner which will be later described, the diaphragm 6 will assume, under the action of spring 39, the position shown in the drawing for positioning the fuel control lever 2 in its fuel cut off or "Stop" position, as above described.

With the diaphragm 26 in a position defined by contact between the end of ring 36 and the wall 23, which positioning will hereinafter be described, and with the follower 40 on the end of diaphragm stem 10 in contact with head 32 of the cylindrical member 31, the diaphragm 6 will be positioned in its intermediate position above mentioned and as shown in Fig. 3. With the diaphragm 6 in this intermediate position the lever 15 will position the fuel control valve lever 2 in "Idle" position.

The operator's control valve device 5 may be of any conventional self-lapping type. By way of example it may comprise a casing having a chamber 45 open to the fluid pressure supply pipe 29 and containing a supply valve 46 arranged to control flow of fluid under pressure from said chamber through an opening 49 to a chamber 47 which is open to the speed control pipe 8. The casing is provided, in chamber 45 around the opening 49, with a seat for the supply valve 46, and a spring 48 in chamber 45 acts on said valve for urging it toward its seat.

The supply valve 46 has a stem loosely extending through opening 49 into chamber 47 and having on its end a release valve 50. The release valve 50 is arranged to cooperate with a seat 51 provided on one side of a movable piston 52 to control communication between chamber 47 formed at one side of said piston and a passage 53 in said piston. Passage 53 leads to a chamber 54 at the opposite side of piston 52 and said

chamber is open to atmosphere through a passage 55. Slidably mounted in the casing above piston 52 is a plunger 56 which is operatively connected to said piston by a control spring 57. A light bias spring 58 in chamber 47 acts on piston 52 urging said piston in a direction away from the release valve 50.

The plunger 56 is engaged by an adjustable screw 59 secured in the end of an arm 60 projecting from an operator's control lever 61 which is mounted to turn on a pin 62 secured in a projection of the casing. The operator's control lever has a "Stop" position, an "Idle" position and a "Full speed" position, which positions it will be noted correspond to the positions of the fuel control lever 2.

In operation, let it be assumed that pipe 29 is supplied with fluid under pressure from any suitable source. Fluid under pressure thus provided in pipe 29 equalizes into diaphragm chamber 25 in the speed and stop control device 3, wherein it acts on diaphragm 26 to deflect said diaphragm to the position shown in the drawing as defined by contact between stop 34 and the casing. Diaphragm 26 will then remain in this position as long as the supply of fluid through pipe 29 to chamber 25 is maintained.

Fluid under pressure supplied to pipe 29 also flows into supply valve chamber 45 in the operator's control valve device 5. Let it now be assumed that the operator's control lever 61 is in "Stop" position. In this position the arm 60 is elevated to such an extent as to allow full expansion of control spring 57 and movement of piston 52 and plunger 56 by spring 58 to the positions shown in the drawing in which said piston is out of contact with the release valve 50 and which permits closing of the supply valve 46 by spring 48. With the release valve 50 unseated, the speed control pipe 8 and thereby chamber 7 in the speed and stop control device 3 will be open to atmosphere past said valve through passage 53 in piston 52 and thence through chamber 54 and passage 55. With diaphragm chamber 7 thus vented, spring 39 will urge the end of stem 10 into contact with head 32 of the element 31 and thus position diaphragm 6 and the fuel control lever in the positions shown in the drawing, it being noted that this position of lever 2 is its "Stop" position for stopping the engine.

Movement of the operator's control lever 61 from its "Stop" position to "Idle" position will actuate arm 60 to urge plunger 56 downwardly to compress spring 57 and when the pressure of said spring is thus increased sufficiently, said spring will move piston 52 against the opposing pressure of bias spring 58 into seating engagement with the release valve 50 and then move said valve to open the supply valve 46 against the opposing pressure of spring 48.

When the supply valve 46 is opened as just described, fluid under pressure will flow from chamber 45 to chamber 47 and thence through the speed control pipe 8 to diaphragm chamber 7 in the speed and stop control device 3. In chamber 47 the pressure of fluid supplied past the supply valve acts on piston 52 in opposition to pressure of spring 57, so that as the pressure in said chamber and in diaphragm chamber 7 of the speed and stop control device increases, such pressure will move piston 52 against the opposition offered by said spring and permit closing of the supply valve 46 when said pressure is increased to a 75 degree corresponding to the movement of lever

61 from "Stop" position to "Idle" position and thus in accordance with the degree of displacement of plunger 56 from the position in which it is shown in the drawing.

In the speed and stop control device 3, the pressure of fluid provided in chamber 7 will deflect the diaphragm 6 toward the left hand against the increasing force of spring 39 and to a position in which the force of said spring balances the opposing pressure of fluid in chamber 7 acting on diaphragm 6, at which time deflection of said diaphragm will cease.

This deflection of diaphragm 6 toward the left hand acts through lever 15 and link 17 to pull the fuel control lever 2 out of its "Stop" position in the direction of its "Idle" position, and when such deflection ceases in a position in which said diaphragm is shown in Fig. 2 and which corresponds to the "Idle" position of the operator's control lever 61, the fuel control lever 2 will be in its "Idle" position.

With the fuel control lever 2 in "Idle" position providing for supply of fuel to the engine in an amount to allow operation of the engine at the minimum or idling speed, the engine may be started in any conventional manner and it will then run on fuel at the idling speed.

If the operator now desires to accelerate the engine he will move control lever out of "Idle" position in the direction of its "Full speed" position in order to move plunger 56 further in a direction to compress spring 57. When due to this further movement of the plunger the pressure of spring 57 is increased sufficiently to overcome the pressure of fluid in chamber 47, said spring will move piston 52 against the opposing pressure of spring 58 and again open the supply valve 46. Fluid under pressure will then again flow to chamber 47 and then to diaphragm chamber 7 in the speed and stop control device 3. As the pressure of fluid thus supplied to chamber 47 and acting on piston 52 is then increased, the piston 52 will again move against the opposing pressure of spring 57 and finally permit the supply valve 46 to close when said pressure is increased to a degree corresponding to the position of the operator's control lever 61. This increase in pressure of fluid in diaphragm chamber 7 will deflect the diaphragm 6 to a new position in which said pressure is balanced by spring 39, and this movement of diaphragm 6 will pull the fuel control lever 2 out of its "Idle" position to a position corresponding to that of the operator's control lever 61 to thereby provide the desired increase in speed or output of power of the engine.

If the operator desires to further accelerate the engine, he may move the control lever 61 further in the direction of its "Full speed" position and a corresponding change in position of the fuel control lever 2 will occur, or if maximum engine speed is desired, movement of the operator's control lever 61 to its "Full speed" position will effect like positioning of the fuel control lever 2, as will be apparent from the above description.

If the operator now desires to reduce the speed of the engine he will move lever 61 in the direction toward its "Idle" position. This will permit displacement of plunger 56 by spring 57 and consequently a reduction in the force of said spring on piston 52. When the pressure of spring 57 on piston 52 is thus reduced to a degree below the opposing force of the pressure of fluid in chamber 47, the fluid pressure in said chamber will move said piston out of contact with the re-

lease valve 50, whereupon fluid under pressure will be released past said valve from said chamber and from diaphragm chamber 7 in the speed and stop control device 3. As the pressure of fluid is thus reduced in chamber 7, spring 57 will move piston 52 back toward the release valve 50 and finally into engagement with said valve to prevent further release of fluid under pressure. The pressure of fluid in chamber 47 and in diaphragm chamber 7 will thus be reduced to a pressure which corresponds to the position of the operator's control lever.

As fluid under pressure is released from diaphragm chamber 7 in the speed and stop control device, the diaphragm 6 will be moved by spring 39 to a new position corresponding to the reduction in such pressure, and, as a result, the fuel control lever 2 will be moved toward its "Idle" position to a position corresponding to the position of the operator's control lever 61.

Movement of the operator's control lever 61 further in the direction of its "Idle" position will again cause operation of the speed and stop control device 3 to correspondingly change the position of the fuel control lever 2, while movement of the operator's control lever to its "Idle" position will result in movement of the fuel control lever 2 to its "Idle" position, as will be apparent from the above description.

It will be evident that if the operator's control lever 61 is moved to its "Stop" position for effecting a complete release of fluid under pressure from the speed control pipe 8, the fuel control lever 2 will be returned to its "Stop" position by operation of spring 39 to move the stem 16 back into contact with the head 32 of member 31.

The above described operation is the normal or desired and intended operation of the apparatus whereby the fuel supply to the engine may be cut off to stop the engine, or may be varied in amount to cause operation of the engine at any selected speed or degree of output between and including idling and full speed, by the operator merely moving the control lever 61 to a selected position. It will be noted that this desired operation is dependent upon the diaphragm 26 occupying the position in which it is shown in the drawing and which position is dependent upon maintenance of the supply of fluid under pressure to pipe 29 and in diaphragm chamber 25.

Now let it be assumed that the operator's control lever 61 is in "Idle" position providing in diaphragm chamber 7 fluid at the pressure required to position fuel control lever 2 in its "Idle" position and that the engine is operating at minimum or idle speed. With this condition existing, let it further be assumed that the supply of fluid to pipe 29 fails, due for example to breakage of said pipe. A loss of fluid pressure in chamber 25 will then result, and spring 39, being held under pressure by pressure of fluid in chamber 7 on diaphragm 6, will then act to move the ring 36, member 31 and diaphragm 26 toward the left hand to the position defined by contact between said ring and the casing wall 23, as shown in Fig. 3 of the drawing. The same operation will result in case of loss of fluid under pressure from pipe 29 and diaphragm chamber 25 regardless of the speed at which the engine may be operating at the time of such loss.

As the diaphragm 26, member 31 and ring 36 are moved by pressure of fluid in chamber 7

upon loss of fluid under pressure from chamber 25 as just described, the deflection of diaphragm 6 to cause such movement will of course cause acceleration of the engine, but this is not objectionable in the emergency. However, the operator by moving the control lever 61 to "Stop" position can release all fluid under pressure from chamber 7 to cause the engine to promptly decelerate with all fluid under pressure released from chamber 7, the rod 10 will be moved to the position defined by contact between said rod and head 32 of member 31, but with ring 36 in contact with wall 23, the rod 10 will be stopped in the position (Fig. 3) in which the fuel control lever 2 is in "Idle" position. Thus movement of the operator's control lever 61 to "Stop" position with fluid under pressure vented or lost from chamber 25, can only cause operation of the fuel control lever 2 to reduce the speed of the engine to idling and the engine will not stop, but will be kept running in the emergency.

From the above description it will be noted that to prevent stopping of the engine in the event of loss of the supply of fluid under pressure to pipe 29 and diaphragm chamber 25, fluid under pressure must be maintained effective in chamber 7 on diaphragm 6 to pull ring 36 into contact with wall 23. As will be apparent, this condition will result if the supply valve 46 in the operator's control device 5 remains seated under the action of spring 48 upon the loss of fluid under pressure from chamber 45. If under this condition the pressure of spring 48 is however inadequate to maintain the valve 46 seated against the pressure of fluid effective in chamber 47, said valve will open and release fluid under pressure from chamber 47 and diaphragm chamber 7, but if the spring closes the valve while sufficient pressure is still effective in diaphragm chamber 7 to cause movement of the parts including ring 36 to their left hand position (Fig. 3), the desired result will be obtained.

If the valve 46 should remain open and permit pressure of fluid in diaphragm chamber 7 to reduce with the reducing pressure in chamber 25 to a sufficiently low degree, the structure would not however operate, and assuming that valve 46 might thus remain open, a choke 64 is provided to restrict the release of fluid under pressure from diaphragm chamber 7. Except in case the valve 46 should remain open as just described this choke could be dispensed with. In case the valve 46 remains open however, this choke will so restrict the release of fluid under pressure from chamber 7 with respect to the release or loss of fluid under pressure from chamber 25 as to maintain sufficient pressure on diaphragm 6 to move the parts including ring 36 to their left hand position (Fig. 3). After the parts attain their left hand position, if the valve 46 is still open and remains so, a complete release of fluid under pressure from chamber 7, and reduction in speed of engine 1 to idling, will occur without the operator moving his control lever 61 to "Stop" position.

The choke 64 may be located in pipe 8 in a by-pass communication around a check valve 65 having greater flow capacity in the direction of chamber 7 than choke 64, so that said choke will not act to retard acceleration of the engine in response to movement of the operator's control lever 61.

With the engine still running after the loss of supply fluid pressure, the operator by operating the auxiliary lever 4 may shift the fuel control

lever 2 to obtain any speed of the engine which he may desire. To subsequently stop the engine the operator may operate the auxiliary lever 4 to pull the fuel control lever 2 to its "stop" position, if he so desires.

Having now described my invention, what I claim as new and desire to secure by Letters Patent is:

1. In combination, a source of fluid under pressure, an adjustable member having two different positions, control means operable by fluid under pressure to move said member from one of said positions to the other position, mechanism connected to said control means for operating said control means to move said member to said one position upon release of fluid under pressure from said control means, other control means operable by pressure of fluid in said source to render said mechanism effective, and upon loss of fluid under pressure from said source ineffective, and means for supplying fluid under pressure to and releasing fluid under pressure from said control means.
2. In combination, a source of fluid under pressure, an adjustable member, actuating means for adjusting said member, control means comprising a spring, a casing, a movable element in said casing connected to said actuating means and movable by fluid under pressure against said spring to actuate said actuating means to adjust said member, and cooperating means cooperable with said element to control said actuating means and conditionable by fluid under pressure from said source to render pressure of fluid on said element effective to provide a certain adjustment of said member, said cooperating means being operable by said spring upon loss of pressure of said source thereon to render pressure of fluid on said element effective to provide a different adjustment of said member.
3. In combination, a source of fluid under pressure, an adjustable member, and means for controlling the adjustment of said member comprising a spring, a casing, a first movable element in said casing movable by fluid under pressure against said spring to adjust said member, a second movable element in said casing for controlling the pressure of said spring on said first movable element and adjustable to different positions to provide the same pressure of said spring on said first movable element in correspondingly different positions of said first movable element, said second element being subject directly to pressure of fluid in said source and being movable to one of its positions by pressure of fluid in said source and to a different position upon relief of pressure of fluid from said source; and means for supplying fluid under pressure to act on said first movable element and for releasing such fluid pressure.
4. A control apparatus comprising in combination, a source of fluid under pressure, a spring, a casing, a first fluid pressure controlled movable element in said casing, movable, when not subject to pressure of fluid, by said spring to a stop position and movable against said spring by fluid at a certain pressure to an idle position and being movable past said idle position when subject to fluid at greater pressure, a second movable element in said casing subject to fluid under pressure from said source, means operable by said second movable element when subject to pressure of fluid from said source to condition said spring to move said first movable element from its said idle position to its stop position, and

operable upon loss of fluid under pressure from said source to render said spring ineffective to move said first movable element from its said idle position to its said stop position upon release of fluid under pressure on said first element, and means operable to supply fluid under pressure to and to release fluid under pressure from said first element.

5. A control apparatus comprising in combination, a source of fluid under pressure, a spring, 10 a casing, a first fluid pressure controlled movable element in said casing movable, when not subject to pressure of fluid, by said spring to a stop position and movable by fluid at a certain pressure to an idle position and being movable past said idle position when subject to fluid at greater pressure, a second movable element in said casing conditionable by fluid under pressure from said source to render said spring effective to move said first movable element from its said idle position to its stop position, said spring being operable by pressure of fluid on said first element upon loss of fluid under pressure from said source to actuate said second movable element to render said spring ineffective to move said first movable element from its idle position to its stop position upon release of fluid under pressure on said first movable element, control means for controlling pressure of fluid on said first movable element comprising a supply valve operable to supply fluid under pressure from said source to act on said first movable element, the pressure of fluid effective on said first movable element being operable to open said supply valve upon loss of fluid under pressure from said source, and a spring acting on said supply valve operable upon loss of fluid under pressure from said source to close said supply valve against pressure of fluid required on said first movable element to operate said second movable element to render the first named spring ineffective to move said first movable element to stop position upon release of fluid under pressure on said first movable element.

6. A control apparatus comprising in combination, a source of fluid under pressure, a spring, a casing, a first fluid pressure controlled movable element in said casing movable, when not subject to pressure of fluid, by said spring to a stop position and movable by fluid at a certain pressure to an idle position and being movable past idle position when subject to fluid at greater pressure, a second movable element in said casing movable to one position by fluid under pressure from said source to render said spring effective to move said first movable element from its said idle position to its said stop position upon release of fluid under pressure on said first element, said second element being movable by said spring to another position to render said spring ineffective to move said first element past its idle position to its stop position upon release of fluid under pressure on said first element, control means for controlling pressure of fluid on said first element comprising a supply valve operable to supply fluid under pressure from said source to act on said first element and which pressure is effective to open said supply valve upon loss of fluid under pressure from said source, and means operable upon loss of fluid under pressure from said source and on said second movable element and upon said opening of said supply valve to so restrict release of fluid under pressure from said first element as to maintain adequate pressure on said first element to actuate said spring to move said second element to said other position.
